ARTIST'S CANVAS PAD

Stan M. Silver, New York, N. Y.

Application April 9, 1949, Serial No. 86,477

7 Claims. (Cl. 41—4)

1

The present invention relates to a tear-off pad, for artists and more particularly to a canvas or the like tear-off pad suitable for painting in oils and other slow drying media.

Certain kinds of tear-off pads for artists' use with dry or quick drying media have heretofore been known and found highly desirable, since they provide numerous prepared drying surfaces in convenient arrangement for drying thereon and in compact form, which occupies but little space and is easy and convenient to store and to carry from place to place, and from which each drawing can be easily removed, as completed, to uncover a new, fresh surface for drawing.

However, such tear-off pads, though highly advantageous for use with dry or quick drying media, have presented no advantages for use in painting with slow drying media such as oil paints or the like, and have, in fact, been highly undesirable for such use, since, after a slow drying painting is completed it cannot be conveniently removed and disposed of because of the wetness of the surface, as such wetness might cause the oil to flow and the lines of the drawing to become distorted and obliterated with the bending or creasing during removal. Nor could the completed, wet painting be left on the pad and conveniently carried by the artist from location to location, as he is generally required to do after completing a painting on one location, for the same reason that a wet surface which would smudge if it should come in contact with the pad cover or with other articles. As a consequence, no practical canvas or like tear-off pads for artists have heretofore been produced.

It is the general object of the present invention, therefore, to provide a practical artist's tear-off pad of canvas or the like suitable for use, with all the aforesaid advantages and conveniences, for painting in oils and other slow drying media.

It is a specific object of the present invention to provide a tear-off pad, of canvas or the like, for artists, on which painting with slow drying media may be done and which may be readily, conveniently and compactly disposed of and transported from location to location before it is dry without danger or risk of smudging or otherwise damaging the painted surface.

The foregoing and other advantages and superiorities of the artist's canvas pad of the present invention will become more readily apparent to those skilled in the art from the embodiment thereof shown in the accompanying drawings and from the description following. It is to

2

be understood, however, that such embodiment is shown by way of illustration only to make the principles and practice of the present invention more readily comprehensible, and without any intent of limiting the invention to the specific details therein shown.

In the drawings:

Fig. 1 is an isometric view of an artist's canvas pad of the present invention shown with the cover in partly open position; the broken lines showing a cover guard element in operative position;

Fig. 2 is an end view of the pad of the present invention shown with the cover in closed position and the guard in operative position; and

Fig. 3 is an enlarged, fragmentary sectional view taken on line 3—3 of Fig. 2.

Referring more specifically to the accompanying drawings the canvas pad of the present invention comprises a pad generally designated as 10, formed of a plurality of superposed sheets of canvas, 11, of equal size and shape, which sheets may have their upper surface properly treated to receive oil paints thereon. The sheets 11 are maintained in pad formation by means of adhesive, 12, which may be of a plastic character and may be applied substantially completely around the periphery of the sheets, leaving only one corner, as 13, to be grasped for tearing off free.

The pad 10 is fixedly secured by its bottom, in any desired manner, to a rigid baseboard, 14, of a folder or cover, generally designated as 15, which includes a rigid tap or cover board, 16, connected to the base board 14 by a flexible connection, or back, 17, which back 17 is detached and spaced from the pad 10, so that the cover 16 may, when desired, be placed over and against the pad 10 or swung away from it to free the surface of the pad for use.

In order to make possible the transportation of the pad in substantially closed, compact position even when the top sheet of the pad 10 is covered with wet paint, I provide a spacing or guard member, generally designated as 20, at the center of the free, forward edge of the cover 16, which guard or spacing member may, in one position, be placed flat against the inside face of the cover 16 and in another position securely erected perpendicularly to said face so that when the cover 16 is folded towards the pad 10, the spacing member will keep the cover slightly spaced from the surface of the pad 10, to prevent its contact with such surface and yet in substantially closed, compact position, suitable for

convenient disposal for storing or transportation.

While numerous types of guards 20 suitable for the purpose might readily suggest themselves to anyone skilled in the art once the principle of the present invention is disclosed, I have found simplified, readily available and easily and conveniently manipulable means of a standard character highly suitable for the purpose.

Such means comprises a standard type of paper clip, of the type having a head portion, 21, and a pair of leg portions, 22 and 23, respectively, one generally longer than the other and having sharp ends 24 which legs 22 and 23 are readily flexible towards and away from each other.

The cover 16 is provided with an opening, 25, close to its forward edge. In this opening the guard clip 20 is inserted with its head 21 on the exterior of the cover 16 and its legs extending out from the inner face thereof. The legs 22 and 23 are then folded back against the inside face of the cover 16 to lie flat thereagainst, as shown in Fig. 1, permitting a complete closing of the cover 16 against the pad 10 when desired.

When the surface of the pad 10 is wet and it is desired to substantially close the cover 16 without smudging such surface, one of the legs of the clip 20 such as the longer one, 23, may be erected to perpendicular position relative the inner face of the cover 16 so that when the cover is moved its sharp end 24 will contact the surface of the pad 10 on a highly limited area and at a relatively immaterial point adjacent the edge thereof, to keep the cover 16 slightly spaced from the pad 10 along its entire surface, as clearly shown in Fig. 2 of the drawing, this permits the pad to be either laid down or carried in closed position, with its wet surface protected from smudging as well as from dust.

This completes the description of one embodiment of the artist's tear-off pad of the present invention. It will be apparent that numerous modifications and variations thereof may be made therein, by anyone skilled in the art, in accordance with the principles of the invention hereinabove set forth and without the use of any inventive ingenuity. I desire, therefore, to be protected for any and all such modifications and variations that may be made within the spirit of the present invention and the scope of the claims hereto appended.

What I claim is:

1. An artist's pad of the character described, comprising, in combination, a plurality of canvas sheets superposed on and detachably secured to one another, and a folder including a base and a rigid cover flexibly connected to one another along one edge, said canvas sheets secured to said base, and a spacing member on the inner face of said cover adjacent an edge thereof and overlying said canvas sheets, said spacing member foldable against said cover in one position and stiffly erectable relative thereto in another position to have its end contact the uppermost of said canvas sheet.

2. An artist's pad of the character described, comprising, in combination, a plurality of canvas sheets superposed on one another, said sheets detachably secured to one another by an adhesive along substantially their entire peripheries leaving one corner unsecured for grasping, and a folder including a rigid base and a rigid cover flexibly connected to one another along one of their edges, and a spacing member secured to the inner face of said cover adjacent an edge thereof and overlying said canvas sheets, said spacing

5 member including an element foldable against said cover in one position and rigidly erectable relative thereto in another position to have its end contact the uppermost of said canvas sheets.

3. An artist's pad of the character described, comprising, in combination, a plurality of canvas sheets superposed on one another, said sheets detachably secured to one another by an adhesive along substantially their entire peripheries leaving one corner unsecured for grasping, and a folder including a rigid cover flexibly connected to one another along one of their edges, and a spacing member secured to the inner face of said cover adjacent an edge thereof and overlying said canvas sheets, said spacing member including an element having a painted end, said element foldable against said cover in one position and rigidly erectable relative thereto in another position to have its end contact the uppermost of said canvas sheets.

4. An artist's pad of the character described, comprising, in combination, a plurality of canvas sheets superposed on and detachably secured to one another, and a folder including a base and a rigid cover flexibly connected to one another along one of their edges, said canvas sheets secured to said base, said cover having an aperture formed adjacent an edge thereof and overlying said canvas sheets, a spacing member inserted through said aperture, said spacing member including a head portion adapted to engage the edges of said aperture and a pair of leg portions secured to said head portion and extending through said aperture, said leg portions being rigidly flexible and each adapted to be folded against the inner face of said cover in one position and adapted to be erected relative thereto in another position whereby one of said leg portions may be erected to contact the uppermost of said canvas sheets to space the cover therefrom while the other of said leg portions remains folded against the inner face of said cover to retain the spacing member in position.

5. The combination of claim 4, wherein said leg portions have pointed ends.

6. A folder for an artist's pad comprising a base and a cover, said cover formed of a rigid material, said base and cover flexibly connected to one another along one of their edges, said base adapted to have a drawing pad fixedly held thereon, said cover having an aperture formed therein adjacent an edge thereof in position to overlie said drawing pad, a spacing member inserted through said aperture, said spacing member including a head portion adapted to engage the edges of said aperture and a pair of leg portions secured to said head portion and extending through said aperture, said leg portions being rigidly flexible and each adapted to be folded against the inner face of said cover in one position and adapted to be erected relative thereto in another position whereby one of said leg portions may be erected to contact the surface of said pad to space the cover therefrom while the other of said leg portions remains folded against the inner face of said cover to retain the spacing member in position.

7. A folder for an artist's pad comprising a base adapted to have the pad secured thereto and a cover, said cover formed of a rigid material and flexibly connected to said base along one of their edges, and means for selectively spacing said cover from said pad, including a flexible member secured to said cover adjacent an edge thereof, said member adapted to be folded against the inner

5

face of said cover in one position and to be erected perpendicular thereto to contact said pad in another position.
